UNITED STATES PATENT OFFICE.

THOMAS H. MURPHY, OF UTICA, NEW YORK, ASSIGNOR TO JOHNSTON NOVELTY & MILL SPECIALTY CO., OF UTICA, NEW YORK.

MACHINE FOR TURNING AND WINDING TUBULAR FABRICS.

941,164.

Specification of Letters Patent.

Patented Nov. 23, 1909.

Application filed April 15, 1905. Serial No. 255,735.

To all whom it may concern:

Be it known that I, THOMAS H. MURPHY, of Utica, in the county of Oneida and State of New York, have invented certain new and useful Improvements in Machines for Turning and Winding Tubular Fabrics; and I do hereby declare that the following is a full, clear, and exact description thereof, which will enable others skilled in the art to which it appertains to make and use the same, reference being had to the accompanying drawings, and to the characters of reference marked thereon, which form part of this specification.

The object of my invention is to provide an improved machine for turning and winding tubular fabric, which will carefully and expeditiously turn the fabric and wind it in a true and even roll, whereby the goods are kept in the best of condition and free from all cross-draws, transverse strains and wrinkles.

In the drawings Figure 1 shows a plan view of a machine of my improved construction, a section of the turning tube being broken out to reduce the length of the figure. Figs. 2 and 2^a show details of the construction at the end of the turning tube. Fig. 3 is a vertical sectional view of the machine, except as to the turning tube. Fig. 4 is a transverse section of the machine. Fig. 5 shows in perspective a floating spreader employed in the construction.

Referring to the reference letters and figures in a more particular description, 1 indicates the frame of the machine, which is provided with a pair of clamps 1^a and 1^b, securing in position at one end of the frame the turning pipe or tube 2. This tube is ordinarily several feet long and is supported in the clamps at one end only and projects from the machine toward the left, as shown in Figs. 1 and 3, several feet in such manner as to allow the tubular fabric to be turned to be first stripped onto the outer surface of the pipe. This pipe or tube is preferably provided with a flaring delivery end 2^a as shown. On the receiving end of the tube 2 it is provided with a series of rollers 3 supported on the ring 4, which ring is supported by hangers 5, and the rollers may be spaced by projections 6 provided on the end of a ring 7 inserted in the receiving end of the tube 2. Mounted on the opposite end of

the frame 1 from the turning tube and arranged substantially in line with the tube in a horizontal plane, are the drawing rollers 8 and 9 mounted on shafts to rotate freely. The shaft of the roller 9 is extended to receive the band wheels 10, by means of which power may be applied to the shaft, and the shafts of the rollers 8 and 9 are coupled together so as to drive both by means of the intermeshing gears 11. The roller 8 is arranged in advance of the roller 9, and while the upper surface of the roller 8 is substantially in line with the horizontal plane of the axis of the tube 2, the under surface of the roller 9 to the rear is somewhat below this plane. In the vertical plane and at either end of the roller 9 there is provided vertically grooved standards 12, the grooves of which receive the ends of the accumulating roller 13, which roller, with or without a roll of fabric thereon, rests and floats on the roller 9.

Within the tubular fabric there is adapted to be introduced a spreader 14, consisting preferably of a frame having a pointed or receiving end 14^a and a substantially square delivery end 14^b, with a pair of hold-back rollers 15 mounted thereon and located in the planes immediately above and immediately below the upper and under surfaces respectively of the spreader frame. These hold-back rollers 15 are adapted to engage (the fabric intervening) with the stripping rollers 16—16 supported in bearings on the frame 1 immediately in advance of the roller 8. These rollers 16 are driven in connection with rollers 8 and 9, and preferably at a little higher rate of peripheral speed. The train of gears for driving the rollers 16 is shown at 25.

Sliding laterally on the rollers 16 are provided the fabric edge guides 17—17. These plates 17 are provided with screw-threaded nuts 17^a engaging with the right and left threaded screw 18. The screw 18 is provided with hand wheel 19, by which it may be rotated, and by this means the guiding plates 17 may be simultaneously adjusted toward or from the central line of the machine.

In operation a quantity of tubular fabric to be turned is stripped on to the outer surface of the turning tube 2. The end last stripped on to the tube is then passed

2
through the tube toward the drawing rollers. When a sufficient quantity has been brought up to the drawing rollers, the spreader 14 is inserted and the end passed 5 through the rollers 16, over the roller 8, under the roller 9 and engaged with the accumulating roller 13. The guides 17 having been suitably adjusted, the machine is started and the fabric is drawn from off the outer 10 side of the tube 2, through the inner side, over the spreader 5 and wound on the accumulating roller. The floating spreader 14 is prevented from moving with the fabric by the rollers 15 engaging with the rollers 16, 15 the fabric intervening, however, and the arrangement is preferably such that the delivery end 14^b of the spreader engages with the upper surface of the roller 8, the fabric intervening, whereby the spreader is steadied 20 and any tendency to bind at any point is obviated.

It may be noted that the spreader must float in such a way as to avoid any material pinching or binding, for if this occurs the 25 fabric can not be drawn and wound satisfactorily upon the accumulating roller.

When the piece has been run through the machine, the accumulating roller will preferably be removed and another one substituted, and another piece of goods to be operated upon applied as before mentioned.

The clamps 1^a and 1^b may be extended upwardly as shown particularly in Fig. 3 to support another turning tube 20 of smaller 35 diameter, which will be found useful for turning tubular fabric of a small diameter. When using this tube, the fabric as it passes out from the delivery end of the tube 20 will pass downwardly to the rollers 16 in an inclined direction, as indicated by dotted lines at 21. The tube 2 will ordinarily serve for a number of the larger sizes of tubular fabric, but spreaders 14 of various sizes will need to be provided to correspond with the 45 particular size of the fabric being operated upon.

Changes and modifications in and from the construction herein described may be made without departing from the spirit of 50 my invention.

What I claim as new and desire to secure by Letters Patent is:

1. The combination in a turning and winding machine for tubular fabrics of a frame, drawing and winding rollers mounted in the frame, upper and lower stripping rollers arranged adjacent to the drawing and winding rollers, a floating spreader having a pair of holdback rollers, a turning tube supported at the end adjacent to the 55 rollers in the frame, and projecting away from the frame in a line substantially at right angles with the rollers, in a free end adapted to receive tubular fabric on the outside and deliver it through the tube to the 60 rolls, the end of the tube adjacent to the rolls being arranged with reference thereto to afford a space for the spreader, substantially as set forth.

2. In a turning and winding machine, the combination with a frame, of a turning tube supported by said frame, drawing and winding rollers, upper and lower stripping rollers, and a floating spreader having a pair of holdback rollers coöperating with 65 said stripping rollers.

3. In a turning and winding machine, the combination with a frame, of a turning tube supported by said frame, a drawing and winding roller, upper and lower stripping 80 rollers, a floating spreader extending between said stripping rollers and having its end adjacent said drawing and winding roller, and a pair of holdback rollers on said spreader coöperating with said stripping 85 rollers.

4. In a turning and winding machine, the combination with a frame, of a turning tube supported by said frame, upper and lower stripping rollers, and a floating spreader 90 having a pair of holdback rollers coöperating with said stripping rollers.

In witness whereof, I have affixed my signature, in presence of two witnesses, this 10th day of April 1905.

THOMAS H. MURPHIY.
